UNITED STATES PATENT OFFICE.

SHINTARO MAESHIMA, OF TOKYO, JAPAN.

MAGNETIC HEALING APPARATUS.

1,421,516.

Specification of Letters Patent. Patented July 4, 1922.

Application filed May 2, 1918. Serial No. 232,184.

To all whom it may concern:

Be it known that I, SHINTARO MAESHIMA, a subject of the Emperor of Japan, residing at No. 31 Tansu Machi, Ushigome Ku, 5 in the city of Tokyo, Japan, have invented certain new and useful Improvements in Magnetic Healing Apparatus (for which I have filed application in Japan July 3, 1916, No. 26,384), of which the following is a 10 specification.

This invention relates to an apparatus for promoting health and healing diseases by transmitting magnetism into the human body, and consists in a mixture of powders 15 of magnetite, antimony sulphide and charcoal sealed in a metal casing, through which one or more copper rods are passed, the magnetism caused in the mixture being transmitted into the human body by means 20 of a leading cord.

The object of this invention is to provide an apparatus for transmitting magnetism into the human body, which giving a slight stimulus to the nerve periphery and tissue 25 cells, accelerates blood circulation and skin excretion and regulates the metabolism, thereby promoting health and keeping off diseases or assisting recovery therefrom. Another object is to provide an apparatus 30 adapted for the above purpose, which is easy of use, gives no bad effects, and can be used for any length of time without replenishing any chemical or replacing any part thereof.

As is well known, electric current has long 35 since been used for therapeutical purposes, but no one has ever thought of using magnetism for the similar purposes, employing an apparatus which can be used forever without replenishing any chemical, in which 40 the action of magnetism can be regulated by merely cooling the body of the apparatus, and which can be used by a person even of delicate health or seriously ill.

It has been observed that when a magnet 45 is brought into contact with a sensitive part of the body, such as temple, finger, or tongue, a certain stimulus or sensation is felt, but it soon disappears. It has also been observed that this stimulus or sensation 50 continues so long as the temperature of the body and that of the magnet are kept different, and that the greater the difference of temperature between the two, the stronger is the magnetic action. This clearly shows

that magnetism acts upon the human body 55 and that when the temperature of the body and that of the magnet become equalized such magnetic action disappears.

Taking advantage of my discovery of the above fact and for the purpose of obtaining 60 strongest magnetic action, I have invented an apparatus shown in the annexed drawing in which—

Fig. 1 is a general perspective view of my apparatus, Fig. 2 a vertical section, and 65 Fig. 3 a horizontal section.

To a metal bottom piece 1 are fixed copper rods 2 (in the drawing the apparatus is shown with two such rods, but one or more than two may be used as well) by 70 screwing or soldering. The body of casing 3 which is a metal cylinder, is soldered to the bottom 1 and filled with a mixture 4 of 30 parts of powdered magnetite, 15 parts of powdered antimony sulphide and 45 parts 75 of powdered charcoal (these proportions may be varied according to the quality of the ingredients). The copper rods are for the purpose of concentrating magnetic lines of force. Then the casing is tightly closed 80 with a metal top piece 5. This metal top piece has at its centre a rod 6 vertically fixed thereto, with a hole 7 near its base to receive a leading cord 10. A washer 8 which has a groove on its upper surface all round 85 is placed upon rod 6 and one end of the leading cord 10 inserted in the hole 7, the part projecting beyond the hole being wound around the rod 6 and laid it in the groove of the washer 8. Another washer 90 8' which has a groove on its under surface corresponding to the groove of the other washer is then placed in position, and the whole is held tight by screwing down a nut 9. The leading cord continues single for 95 a convenient length, say one metre, and then separates into two lines, to the end of each of which lines a terminal plate 11 is attached. The terminal plates have each a concave part 12 at the center and are provided with rubber bands 13 for the purpose of tying them to the body of the user.

To use this apparatus, the concave part of the terminal plates filled with absorbent cotton or the like, suitably moistened, and tied 105 to suitable parts of the body, say one to the right, or left, leg and the other to the left, or right, arm, if the purpose is to place the

- whole body under magnetic influence, or to near the affected parts, if it is intended to obtain cure of any disease. To obtain a greater magnetic force, the apparatus should 5 be cooled by placing it in water, or when necessary, in iced water, contained is a vessel which must be either porcelain or glass, and the parts of the body where the terminal plates are applied should be kept warm by 10 covering them with cloth moistened with hot water.

- When there is a certain difference of temperature between the apparatus and the body of the user thereof, magnetic influence begins to appear, which becomes stronger and stronger as the difference of temperature between the two becomes greater and greater, that is, as the apparatus becomes cooler and cooler. 15
- 20 The stimulus which this apparatus gives to the human body is very natural and penetrating in action, very slow and rhythmic, flows into the innermost cells and gives very salutary effects. The more important of 25 these effects are regularity of pulsation, viscosity of veins, prolonged respiration, and so on, and thus promote the normal physiological functions. A sphygmometer shows a rise of 3 or 4 mm. after using this apparatus for from 5 to 10 minutes. Further 30 application of it shows a rise of 20 or 30 mm., and sometimes the person using it perspires. Of course, the period after which such reactions take place, differs according 35 to the constitution and age of the user, but generally speaking it is about two hours with the adult and about 30 minutes with the child. The record of a sphygmograph also shows very sound condition of pulsation. 40

To recapitulate, the more important ef-

fects obtained by the use of this apparatus are as follows:—

- Increase of blood pressure. 45
 Regular pulse.
 Prolonged respiration.
 Increase of warm sensation.
 Perspiratory action.
 Diuretic action.
 Analgesic action.
 Peristaltic action. 50
 Increase of appetite.
 Vital compensation.

The apparatus of my invention, as has been explained, works forever without the expense or trouble of replenishing any chemical, and is useful to all persons, as it keeps them from sickness, or when they have become sick, it assists recovery therefrom, by promoting normal vital functions of various organs of the human body. 55 60

Having now fully described my invention, I claim:—

1. A therapeutic appliance comprising a metallic casing, a mixture of magnetite, antimony sulphide and charcoal contained within said casing, copper in rod form passing through said mixture, terminal plates for application to the body and electrical connections from said plates to the casing, substantially as described. 65

2. A therapeutic appliance comprising a metallic casing, a mixture of magnetite, antimony sulphide and charcoal, all in powdered form, contained within said casing, copper 75 in rod form passing through said mixture, terminal plates for application to the body and electrical connections from said plates to the casing, substantially as described.

In testimony whereof I have signed my name to this specification. 80

SHINTARO MAESHIMA.
